UNITED STATES PATENT OFFICE

MURRAY WINTER, OF WRENTHAM, MASSACHUSETTS, ASSIGNOR TO THE SURFACE COMBUSTION COMPANY, INC., OF TOLEDO, OHIO, A CORPORATION OF NEW YORK

SPIRAL FEED CONVEYER FOR HEAT-TREATING FURNACES

Application filed September 25, 1928. Serial No. 308,314.

This invention relates to improvements in conveyers. It is an object of the invention to provide a conveyer which shall consist of a shaft having a spiral guide way along which ring gears and the like may be moved into a furnace for heat-treatment. The various features of novelty and invention will more fully appear from the detailed description taken in connection with the accompanying 10 drawings forming part of this specification.

Referring to the drawings wherein the preferred form of the invention is shown:

Fig. 1 shows the invention embodied with a heat-treating furnace which is more or less 15 diagrammatically shown, the conveyer shaft proper being in side elevation and the supporting elements at the near side of the shaft being omitted for clarity of showing;

Fig. 2 is a transverse section on line 2—2 20 of Fig. 1 and showing how the outer end of the conveyer shaft is supported;

Fig. 3 is a transverse section showing how the intermediate portion of the conveyer shaft is supported;

25 Fig. 4 is a view generally corresponding to Fig. 1 but showing shaft supporting means within the furnace;

Fig. 5 is a fragmentary view on an enlarged 30 scale taken substantially on what would correspond to line 5—5 of Fig. 2 and showing the preferred manner of providing against relative axial movement of the shaft and its supporting rollers;

Fig. 6 is a detail view of one of the shaft 35 supporting rollers; and

Fig. 7 is a fragmentary view showing how relative axial movement of the shaft may be prevented by providing a spiral groove in a supporting roller instead of non-spiral ribs 40 or rings as in the other views.

In the drawings, 10 indicates any suitable 45 type of heat-treating furnace provided with a charging opening 12 in one of its end walls and having a bottom discharge opening 14 through which the annular objects may pass out of the furnace, as into a quenching tank, not shown. The furnace may be heated in any suitable manner as by gas or electricity. As shown, the furnace is adapted to be heated 50 by gaseous fuel, reference numeral 16 indi-

cating a series of openings in the side walls of the furnace where gas burners, not shown, may be positioned.

The conveyer comprises a screw shaft generally indicated by letter S. The ring gears or other annular objects to be conveyed are indicated by letter R. The shaft S is shown as extending into the furnace through an opening 12 in the end wall thereof and as terminating short of the opposite end wall 60 above discharge opening 14; but the invention is not limited to this arrangement, the showing being merely illustrative of one mode of using the invention. The objects R are hung on the outer or front end of the shaft S 65 and as the latter rotates the objects will be moved along the shaft by following the channel or guide way 18 formed by a screw thread 19. Where the objects are circular, the rotation of the shaft will impart a slow rotation 70 to the objects,—a feature which is very desirable since a cold spot on the object is thus prevented.

The shaft may be supported by means wholly outside of the furnace as shown in 75 Fig. 1 or partly within the furnace as shown in Fig. 4. Where the supporting means are wholly outside of the furnace the shaft must be strengthened to prevent it from bending as will be readily appreciated. As shown in 80 Fig. 1, the shaft is strengthened by enlarging its diameter from its point of support nearest the furnace and gradually tapering it to its discharge end. The enlarged portion is preferably hollow.

85 The shaft is supported in a cradle of rollers in a manner now to be described. Extending from the shaft are two banks A and B of what for convenience of description may be termed spiral webs or fins 20 and 21, respectively, the webs being radial extensions of the screw thread 19. The diameter of the webs depends on the internal diameter of the annular objects to be conveyed and is such that a proper clearance is provided between 90 the inside bottom of the object and the bottom of the web as clearly shown in Figs. 2 and 3,—it being understood that the inside top of the object rests on the core of the shaft at all times.

The web bank A rests on two plain cylindrical rollers 22 suitably supported in a frame 24. These rollers engage with the webs at points sufficiently removed from the bottom of the webs to permit the annular objects to pass between the rollers as clearly shown in Fig. 3. These rollers preferably also serve as driving rollers, being driven in any suitable manner as by a chain drive 26 receiving power from a motor 28. Top rollers are not necessary since the weight of the shaft serves to hold the shaft properly in place on the rollers as will be readily understood.

The web bank B is supported between pairs of top and bottom rollers 30 and 32, respectively, suitably supported in a frame 34. The bottom rollers 32 bear the same space relation with respect to the bottom of the webs as do the rollers 22 for the web bank A.

It is of course necessary to provide means for preventing axial movement of the shaft and such means will now be described. Referring more particularly to Figs. 1 and 5, it will be noted that the top rollers 30 are provided with non-spiral ribs or ridges 36 of uniform height and axial spacing, these ribs extending completely around the individual rollers. These ribs are adapted to coact with non-spiral grooves 38 formed in the periphery 30 of the webs or fins 21 of the bank B; or, to put the matter in another way, the grooves between the ribs 36 are adapted to coact with teeth-like projections 39 formed on the periphery of the webs 21, the sides of the teeth-like projections being at right angles to the axis of the shaft S. It will now be seen that each complete cylindrical surface of the webs which coacts with the ribbed rollers is provided with a series of grooves 38 and teeth-like projections 39, the lateral or axial spacing thereof being the same as that of the ribs and grooves on the rollers, and as a consequence thereof relative axial displacement between the ribbed rollers and the shaft is effectively prevented. It will of course be understood that it is a matter of choice whether the top or bottom rollers shall be ribbed as aforesaid or whether the main supporting rollers 22 shall be ribbed in which latter event the webs or fins 20 would of course be suitably grooved as already explained.

In Fig. 7, I have shown a modified form of means for preventing relative axial displacement between the shaft S and a coacting roller. In this form of the invention a roller 40 is provided with a spiral groove 42 which runs in a direction which is opposite from that of the spiral web on the shaft, the periphery of the web being preferably provided with teeth 44 adapted to enter corresponding depressions 46 in the roller. The roller should be of the same diameter as the webs for satisfactory operation and on account of its large diameter should be positioned above the axis of the shaft.

In Fig. 4 the shaft S' is shown as supported partly within the furnace by plain rollers 22', the diameter of the core of the shaft being substantially the same from end to end and the spacing of the rollers being the same as that shown in Fig. 3. The outside supporting rollers 22'' are ribbed in the same manner as are the rollers 30 previously described and also serve as driving rollers. Since the shaft is supported adjacent its ends, top supporting rollers are not necessary as regards holding the shaft in place in its cradle of supporting rollers.

A conveying apparatus of the character described is particularly well adapted for heat-treating ring gears. As the conveyer shaft rotates the gears also rotate and are uniformly heated throughout. By reason of the fact that the gears are hung from the shaft, a furnace of limited length will have a relatively greater capacity than a furnace of similar length having a horizontally disposed roller hearth on which the gears must be laid flat.

While the conveyer has been particularly designed for feeding ring gears into a furnace, nevertheless the conveyer is not limited in its application to such use. By reason of the fact that the ring gears project downwardly from the lower portion of the shaft, the conveyer lends itself to other uses. For example, annular objects could very readily be painted by allowing the lower portion of the objects to dip into a tank containing paint it being remembered that the object rotates as the shaft rotates. Other uses will readily occur to those skilled in the art.

Various changes in details of construction may obviously be resorted to without departing from the spirit of the invention.

What is claimed is:

1. In a conveyer, the combination of a horizontally disposed rotatable shaft, spiral means on the shaft forming a guide way for objects hung on the shaft, means arranged alongside of the shaft for supporting it for rotation, said supporting means contacting with the periphery of said spiral means below the axis of the shaft laterally of the bottom thereof, an axially fixed element disposed alongside the shaft, and means on the spiral means cooperating with said element to prevent axial displacement of the shaft.

2. In apparatus of the character described, the combination of a rotatable shaft having a spiral guide way, rollers for supporting the shaft, said guide way being bounded by relatively deep walls where the rollers coact with the shaft, and means for preventing relative axial displacement between the shaft and the supporting rollers.

3. In a conveyer, the combination of a horizontally disposed rotatable shaft, spiral means on the shaft forming a guide way for objects hung on the shaft, means arranged alongside of the shaft for supporting it for

rotation, said supporting means contacting with the periphery of said spiral means below the axis of the shaft laterally of the bottom thereof, the diameter of the shaft opposite

clear the bottom of the screw thread, and said supporting means being arranged laterally of the path of travel of said ring object.

5 said supporting means being increased by a web on the spiral means, and means coacting with said web for preventing relative axial displacement between the shaft and its supporting means.

In testimony whereof I affix my signature. 70

MURRAY WINTER.

10 4. In apparatus of the character described, the combination with a rotatable shaft and rotatable supporting means therefor, of a web projecting radially from and extending spirally around the shaft and coacting with said means to maintain the shaft in spaced relation with respect thereto, said supporting means engaging the periphery of the web at points located laterally of a vertical plane through the axis of the shaft, whereby objects 15 hung on the shaft may be moved longitudinally thereof without interfering with said supporting means.

75

5 5. In apparatus of the character described, the combination with a rotatable shaft and 20 rotatable supporting means therefor, of a web projecting radially from and extending spirally around the shaft; the supporting means and web coacting to support the shaft in a manner to permit objects hung on the 25 shaft to be moved past the points of coaction between the supporting means and web, and a spiral guide way formed as a continuation of the web for moving the objects toward and away from the web.

80

30 6. In apparatus of the character described, the combination with a longitudinally extending cylindrical body, of rollers forming a cradle for supporting said body for rotation, a relatively deep spiral channel formed in the 35 surface of the body where it contacts with said rollers, the body on either side of said channel being of reduced diameter, whereby objects may be hung on the reduced portion, and means on the reduced portion of the body 40 for moving said objects into said channel.

85

45 7. In a conveyer, the combination with a rotatable shaft having a ridge extending spirally therearound and forming walls between which ring objects may be hung on the shaft, 50 of a web formed as a radial projection of a portion of the ridge, and ribbed rolling means coacting with said web to prevent axial displacement of said shaft.

90

55 8. In a conveyer, the combination with a screw shaft on which objects of ring form may be suspended with the axis of the object below the axis of the shaft, of means tangent to the shaft for supporting it for rotation, said shaft where it coacts with said means 60 being of a diameter greater than the internal diameter of the ring object to be conveyed, the screw being continued through the part of enlarged diameter, the depth of the screw thread at the enlarged portion being such that 65 the bottom portion of the ring object will
